UNITED STATES PATENT OFFICE.

ALBERT J. LARCHER, OF CHICAGO, ILLINOIS, ASSIGNOR TO WYMAN-GORDON COMPANY, OF WORCESTER, MASSACHUSETTS, A CORPORATION OF MASSACHUSETTS.

PROCESS AND APPARATUS FOR FORGING CRANK SHAFTS.

Application filed May 31, 1927. Serial No. 195,406.

The invention relates to the die-forging of crank-shafts and seeks to provide an improved method and apparatus for manufacturing the same, and particularly multi-throw crank-shafts having integral counterweights.

Crank-shafts for the multi-cylinder engines of automobiles and the like, are forged from a rolled steel bar, usually of uniform cross-section and having the grain or fiber of the metal extending lengthwise of the bar. In order that the grain or fiber in the finished shaft shall extend axially of the pins and journals and lengthwise of the crank arms or cheeks, the heated bar of stock is subjected to offsetting or so-called "edging" dies, by which it is bent back and forth at a number of longitudinally spaced points to form the offsets or throws and roughly outline the crank arms, journals and pins of the shaft, and the blank thus formed is then die-forged to bring its parts substantially to the desired contour. The usual bending or offsetting operation tends to stretch and weaken the metal, and this is particularly the case in forging a crank-shaft having a large number of single throws, i. e., one having journals on opposite sides of each throw, since in such a shaft the pins and journals are usually quite short. Furthermore, it is difficult to provide such a bent or offset blank with suitable accumulations of metal for forming integral counterbalancing offsets or other projections. Indeed, it is believed to be quite impractical to do so by methods heretofore in use in the manufacture of automobile engine shafts having journals on opposite sides of each throw and counterbalancing projections on each cheek or crank arm. While some automobile engines are equipped with such shafts to avoid vibration at different speeds, the counterweights are usually bolted or otherwise fastened in position and this method of manufacture is unsatisfactory. The present invention provides an improved forging method and apparatus for the formation of crank-shafts for automobiles and like multi-cylinder engines and especially of shafts having the maximum number of journals and integral counterweights.

In accordance with the present invention, the metal of the bar of stock is accumulated

into protuberances or enlargements, one for each throw, and preferably by turning or rotating the bar and subjecting it to transverse pressure between relatively reciprocating die members. The enlarged portions of the blank are then indented on opposite sides to partially divide the same transversely, and preferably by subjecting the blank to the action of forging dies having pairs of opposed, wedge-shaped die elements, to thereby allocate metal for pairs of adjacent crank arms or cheeks. The blank is then brought substantially to the desired contour by shaping dies. In this way, one or more throws of a crank-shaft can be formed by the application of the pressure of the forming dies to the blank in a direction transverse to the plane of the formed throws, and at the same time, if desired, the arms or cheeks of the throws can be provided with integral counterbalancing projections.

The improvement is hereinafter further set forth in detail, the apparatus employed is illustrated in its preferred forms in the accompanying drawings, and the invention is more particularly defined in the appended claims.

In the drawings:

Fig. 1 is a plan or face view of one of the die members having impressions for forming the blank from the bar of stock and for "breaking down" the blank and thereby roughly forming the journals and throws of an integral counterweighted, multi-throw crank-shaft.

Figs. 2, 3 and 4, are longitudinal sections taken on the lines 2—2, 3—3 and 4—4 respectively of Fig. 1, and illustrating the impressions in both the upper and lower dies.

Fig. 5 is an end view of the upper and lower dies.

Figs. 6 and 7 are cross-sections on the lines 6—6 and 7—7 respectively of Fig. 1.

Fig. 8 is a plan or face view of one of the contour shaping dies.

Fig. 9 is a cross-section thereof on the line 9—9 of Fig. 8.

Fig. 10 is a plan or face view of a die member in which the impressions for forming a multi-throw crank-shaft are somewhat modified.

Figs. 11, 12 and 13 are longitudinal sections

taken on the lines 11—11, 12—12, and 13—13 respectively of Fig. 10, and illustrating both the upper and lower die members.

Fig. 14 is an end view of the die members shown in Figs. 10, 11, 12 and 13.

Fig. 15 is a cross-section thereof taken on the line 15—15 of Fig. 10.

Fig. 16 is a longitudinal section, and Figs. 17, 18 and 19 are cross-sections, illustrating the operation of the dies shown in Figs. 10 to 15 inclusive.

Fig. 20 is a plan view illustrating a modification of the initial impression or die cavity.

Fig. 21 is a longitudinal section on line 21—21 of Fig. 20.

Fig. 22 is a cross-section on line 22—22 of Fig. 21.

Fig. 23 is a partial plan view and Fig. 24 is a section on line 24—24 of Fig. 23, illustrating the operation of the die cavities shown in Figs. 20 to 22 inclusive.

Fig. 25 is a plan view illustrating a modified form of die block.

Figs. 26, 27 and 28 are longitudinal sections taken on the lines 26—26, 27—27 and 28—28 respectively, of Fig. 25.

Figs. 29, 30 and 31 are cross-sections on the correspondingly numbered lines of Fig. 25.

Fig. 32 is a plan view, and Fig. 33 is a cross-section illustrating the operation of the dies shown in Figs. 25 to 31 inclusive.

The die blocks or members are of the usual type employed in steam hammers and presses and in which the upper die block is connected to the piston of the steam hammer and is thereby reciprocated to and from the lower die block. In the drawings, only the adjacent portions of the die blocks containing the cavity-forming impressions are shown. In the form shown in Figs. 1 to 7 inclusive, the upper and lower die blocks 10 and 10' are provided with three impressions *a*, *b*, and *c*, which form three die cavities through which the blank is successively passed. Co-operating impressions in the upper and lower die blocks which form each of these cavities are counterparts. The impressions *a* have longitudinally spaced portions 1 of relatively small cross-section and intermediate recesses 2 of relatively large cross-section. The contracted portions 1 and the enlarged recesses 2 are provided with gradually rounded surfaces which are convex and concave respectively, as most clearly shown in Fig. 2, and are oval in cross-section with the major axes of the oval sections lying in the plane of the parting line of the die members, as shown in Figs. 5, 6 and 7. In the particular form shown, the central and end reduced portions 1 which shape the corresponding journal-forming portions of the blank are preferably somewhat longer than the other portions 1 which shape the other journal-forming portions of the blank. The cavity *a* is also pro-

vided at its opposite ends with portions 3 and 4 for forming reduced and enlarged ends on the bar of stock, and with portions 5 forming a cavity into which the tong-hold of the blank extends.

The impressions *b* are provided with portions 1', 2', 3', 4' and 5', which are quite similar to the corresponding portions of the impressions *a*, except that the major axes of the oval cross-sections of the recesses 2' are vertically disposed instead of horizontally, as shown in Fig. 7, and these recesses are substantially rectangular in longitudinal section, as shown in Fig. 3, instead of oval. The impressions *c* are provided with opposed elements 6 for roughing out the journals of the crank-shaft, and with opposed portions or recesses 7 for outlining the counterweighted throws. Each of these recesses is provided with a pair of opposed, wedge-shaped die-elements 8, one on each of the die members. These pairs of die-elements 8 are arranged in the central transverse portions of the recesses 7, and extend transversely from one side of each recess across the vertical plane of the longitudinal axis of the die cavity and merge into semi-circular recesses 9 (see Figs. 1 and 7), which roughly outline the crank pins.

For convenient, quick handling of the stock during the forging operation and in order that the operation may be completed with a single heating of each bar of stock, the impressions *a*, *b*, and *c* are preferably formed in a single pair of die members. Preferably as shown, the impressions *a* and *b* are formed in the outer portions of the faces of the die members and which portions do not quite contact when the die members are engaged. The impressions *c* are, as shown in Figs. 5, 6, and 7, preferably formed in the central contacting portions of the faces of the die members.

The rolled steel bar from which the crank-shaft is forged is preferably of uniform cross-section that is larger than the cross-section of the reduced portions 1 of the impressions *a* and is smaller than the cross-section of the recesses 2. If the stock is of square section, it is of substantially the size indicated in dotted lines in Figs. 1 and 2. The heated bar of stock, having a tong-hold formed on one end, is first struck a number of blows while located between the die impressions *a*, the bar being rotated about its longitudinal axis after each blow and preferably through an angle of substantially 90 degrees. In this way, the metal of the stock opposite the portions 1 is reduced in cross-section and the metal which is displaced by these portions is caused to flow into the enlarged portions or depressions 2. Thus, by the application of pressure of the die impressions *a* to the bar of stock transversely of its axis, longitudinally spaced portions of the bar are reduced in cross-section and the cross-section of the intermediate portions is increased to form a series of the enlarge-

ments of protuberances, the reduced portions preferably corresponding in number to the journals of the finished crank-shaft, and the enlargements or protuberances corresponding in number to the throws. In this operation the metal is squeezed and compacted both in the reduced and enlarged portions of the die impressions and in such a manner that the grain or fiber of the metal adjacent the 10 axis and surface of the blank thus formed are respectively substantially parallel thereto. The blank thus formed is substantially a counterpart of these impressions although it may not quite fill their extreme horizontal 15 dimensions, and it is substantially symmetrical with respect to a horizontal plane coinciding with the parting line of the die members.

The blank is then transferred to the "breaking down" impressions *b*, is rotated about its 20 axis through an angle of 90 degrees and is struck a single blow while located in these impressions. As already noted, the impressions *b* are provided with portions 1', 2', 3', 25 4' and 5' which correspond to the portions 1, 2, 3, 4 and 5 of the impressions *a*, and engage corresponding parts of the blank. By these die impressions the metal of the blank is compressed and the surfaces of the reduced 30 portions are brought more nearly parallel to its axis, and the side faces and the peripheral portions of the protuberances or enlargements are brought more nearly at right angles and parallel respectively to the blank axis.

The blank is then rotated through an angle 35 of substantially 90 degrees and is struck a number of blows while located in the die impressions *c*. The portions 6 of these die impressions, which engage the reduced portions, rough out the journals of the crank-shaft and the opposed die elements 8 having wedge-shaped faces partially divide or split each of the enlargements or protuberances of the blank to thereby allocate metal for pairs 40 of adjacent counterweighted crank arms. In the particular form shown, the die elements 8 also cooperate with the portions 7 and 9 of the die impressions *c* to rough out the counterweighted crank arms and pins of the 45 throws. It is noted that in this dividing or splitting operation, each protuberance of the blank is held or locked between two of the reduced or journal-forming portions 6 of the dies so that the metal displaced by the die elements 8 is forced to flow transversely and 50 compactly fills the portions 7 and 9 of the die cavity. When the die members are in engagement, the opposed wedge shaped edges of the elements 8 are spaced some distance apart 55 so that they do not completely divide the portions of the protuberances of the blank engaged thereby, but the metal of the protuberances or enlargements of the blank is allocated and roughed out to form the crank pins 60 and counterweighted cheeks of the throw by

the application of pressure transversely to the plane of the formed throws and which plane is coincident with the parting line of the dies. When operated upon by the die impressions *c*, the metal of the blank substantially fills and becomes a counterpart of these die impressions, although, preferably the stock and these impressions are so related that no excess metal is squeezed out of the impressions.

The blank is then submitted to the action of counterpart die impressions *d* formed in two die blocks or members 11 and 11' (see Figs. 8 and 9). As is clear from these figures, these impressions are provided with portions for bringing the journals, crank-pins, counterweighted crank arms and other parts of the forging substantially to the desired contour, i. e., the contour or shape that the parts should have before the final finishing or machining operation. These die impressions are necessarily designed to force out a small amount of surplus metal along a flash line 12. In the die forging operation the throws are preferably formed all in a common plane. Then, after removing the fin of surplus metal in a suitable flashing die, the crank throws are indexed or brought to proper position by any suitable means and preferably by means of indexing dies such as set forth in my prior Patent No. 1,403,696, dated January 17, 1922. After the indexing or throw-positioning operation, the crank is subjected to the action of setting dies which bring all of its parts to proper form and position for the final machining operation.

With the improved method and apparatus, the entire forging, throw-indexing or positioning and setting can be accomplished with a single heating of the original bar of stock. It is noted that the die-forging operations, including the roughing out of the crank throws, are effected by the application of the pressure of the dies in a direction transverse of the axis of the blank and substantially at right angles to the plane of the throws formed by the dies, and that the metal at the axial portion of the blank is maintained substantially straight throughout. In other words, there is no bending of the axial portion of the blank in an offsetting or edging die, and consequently there is no stretching of the metal. Instead, the entire forging operation is a compacting or squeezing of the metal of the stock. Notwithstanding the fact that there is no bending of the blank in an edging die, as in prior practice, the grain of the metal in the finished forged crank-shaft is properly disposed axially of the journals and pins and substantially lengthwise and parallel to the surfaces of the crank arms. The improved method and apparatus also provides for the manufacture of a crank-shaft in which the throws have integral forged counterweights, and it is believed that the pres-

ent invention is the first to provide a satisfactory method and means for die-forging an integral crank-shaft having the maximum number of journals and integral counter-weighted crank arms. Although the throws of the crank-shaft are preferably roughed out and brought to the desired contour by forging all of the throws in a common plane, and then positioning the formed throws, the method could be modified by forging the throws at least partially in position. But in any event, in accordance with the present improved method, the throws are roughed out and brought to the desired contour by the application of the pressure of the forging dies in a direction transverse to the plane or planes of the formed throws. While, as set forth, the present method and apparatus are particularly designed and adapted for the manufacture of counterweighted crank-shafts, they are believed to be applicable to the formation of pairs of closely adjacent transverse arms or projections on other like forgings.

In the modification shown in Figs. 10 to 15 inclusive, the impressions *b* and the second forging step above described are omitted and the impressions *a'*, *c'* and *d'* are all formed in a single pair of die blocks or members 13 and 13'. The blank forming and roughing out impressions *a'* and *c'* are formed in the outer portions of the faces of the die blocks that are spaced slightly apart when the die blocks are engaged and the shaping die cavity *d'* is formed in the central meeting portions of these faces. The impressions *a'* are substantially similar to the impressions *a* of the die blocks 10 and 10', and the impressions *c'* and *d'* are quite similar to the impressions *c* and *d*, the slight differences in form being clearly indicated in the drawings.

Figs. 16, 17, 18 and 19 are drawn on the same scale as Figs. 10 to 15 inclusive, and illustrate the operation of the die cavities *a'*, *b'* and *c'*. The original bar of stock of uniform square section except for the tong-hold at one end, is indicated in broken lines in Figs. 16 and 17, and in full lines these figures show the blank formed by the die impressions *a'*, the blank in this form having, as described, portions 1^a of reduced section and portions 2^a of enlarged section. In the impressions *c'*, the enlargements of the blank are partially divided and the journals 6^a, counterweighted crank arms 7^a, and pins 9^a are roughed out and these parts are brought to proper contour, as shown in Fig. 19, by the impressions *d'*. Then, after removing the fin 12^a, the throws are indexed or brought into their proper relative angular positions. Preferably the impressions in the die blocks 13 and 13' are so arranged that the blank is rotated through 180 degrees as it is passed from the impressions *c'* to the impressions *d'*.

Instead of initially subjecting the bar of

stock to a blank forming operation between dies having impressions *a* and *a'* as described, it may be first subjected to "breaking down" or "edging" dies to form the blank having alternately reduced and enlarged portions. Thus the die blocks 14 and 14' (see Figs. 20 21 and 22) which are designed to form the same crank-shaft as the dies 13 and 13', are similar to the latter dies in all respects except that the impressions *b²* are substituted for the impressions *a'*. These impressions have large opposed cavities 15 and pairs of opposed projecting transverse ribs 16 which are preferably provided with rounded edges that are concave in transverse direction as shown in Fig. 22. In this case the bar of stock, while containing the same amount of metal, is rectangular in section and it is subjected to the operation of the impressions *a²* with its wide faces vertically disposed as indicated in broken lines in Fig. 22. The pairs of opposed transverse projections 16 of the die cavity will form the portions 16^a of reduced cross section (see Figs. 23 and 24) and the displaced metal and that in the remaining portions of the bar of stock will form the enlargements 15^a. In this operation the metal contacts only with the central portions of the walls of the die cavity. It is noted that in this "breaking down" operation, the metal of the stock is compacted and is not stretched and the axial portion of the bar is not bent or offset. After this initial operation the blank is rotated about its axis through an angle of 90 degrees and is then subjected to die impressions like the impressions *c'* and *d'* of the die blocks 13 and 13', and is successively brought to the forms shown in Figs. 18 and 19.

The dies previously described are particularly designed for forming six-throw, seven-bearing crank-shafts having a counterweight on each crank arm. The improved process and apparatus are also adapted for forging crankshafts having uncounterweighted single throws, or in which only some of the throws are counterweighted. Thus the dies shown in Figs. 25 to 31 inclusive are designed to form an eight-throw, nine-bearing shaft with counterweights on the two end and the two central crank arms. In the drawings, only the portions of the dies for forming the two central throws and the three throws on the one side of the central throws are shown, but the parts for forming the throws on the other side of the central throws are of similar form.

The die blocks 17 and 17', like the dies 13 and 13' previously described, are provided with blank forming, roughing out and finishing die cavities *a²*, *c²* and *d²*. Similarly, also, the impressions for forming the cavity *a²* are provided with portions 21 and 22 of oval and of relatively small and large cross section respectively for shaping the corresponding portions of the blank. But the im-

pressions in the upper and lower dies are not symmetrical counterparts and the portions or cavities 22 which receive and shape the enlargements or protuberances of the blank 5 are not opposed in the upper and lower die blocks. Instead they are alternated or staggered as most clearly shown in Fig. 26, and the enlargements 22^a of the blank (see Figs. 32 and 33), which are subsequently formed 10 into the crank arms and pins, are similarly disposed and are eccentric with respect to the axis of the blank. Also, the upper die block is provided at each end with a narrow cavity 23 and as the stock is rotated between 15 the reciprocating die blocks, metal is forced upwardly into these cavities and thereby allocated for forming counterweights on the crank arms at the opposite ends of the shaft. It is noted that, while quite narrow, the cavities 20 23 are of such size (see Fig. 29) that the metal does not contact with and is not confined by the edge walls thereof. The impression a^2 is also provided in the lower die block with a central cavity 24 into which metal is 25 forced to provide an enlargement which is later formed into integral counterweights for the two central crank arms. A portion of the blank as it is formed in the die cavity a^2 is indicated in broken lines in Figs. 32 30 and 33, and the relative location of the parting line of the die blocks is indicated by the line a^2-a^2 in Fig. 33.

Upon the transfer of the blank from the impression a^2 to the impression c^2 , it is rotated about its axis through an angle of 90 degrees. Here as before the reduced portions of the blank are engaged by journal forming parts 6' and the enlargements of the blank by portions or cavities 7' having oppositely disposed pairs of wedge-shaped elements 8', 35 that partly divide or split the enlargements, and also having portions 9'. The parts 7', 8' and 9' serve in the manner previously described to rough out the crank arms and pins. But in the form shown, only the throw-forming cavities at the center and ends of the impressions c^2 are provided with portions 40 25 for roughing out the counterweights for the two central and the two end crank arms. 45 A portion of the blank shaped by the impressions c^2 is shown in full lines in Figs. 32 and 33 and the relative location of the parting line of the dies is indicated by the line c^2-c^2 in Fig. 33. It should also be noted 50 that the portions 26 of the die blocks on opposite sides of the cavities 6' that form the central journal, engage and divide the enlargement of the blank that is formed in the cavity 24 of the impressions a^2 , and so aid 55 in roughing out or allocating metal for the counterweights on the two central crank arms. The parts are finally brought to the desired contour in the die impressions d^2 .

Throughout the forging operations with 60 the different forms shown, the metal is com-

pacted between opposed die elements, there is little or no stretching of the fiber of the metal and no overlapping or folding of the grain, and the grain or fiber is properly disposed in the finished forging. Other modifications may be made and the details set forth varied without departure from the scope of the appended claims. 70

I claim as my invention:

1. The method of making multi-throw 75 crank-shafts which comprises forming a plurality of enlargements on a rolled steel bar, then, while maintaining the axial portion of the bar substantially straight, breaking down the enlarged portions of the blank 80 to allocate metal to form the throws, and then shaping the throws and journals substantially to the desired contour.

2. The method of making die-forged, 85 multi-throw crank-shafts which comprises forming a substantially straight blank having longitudinal portions of relatively large and small cross-section, then die-forging the blank to form the smaller portions into journals and the larger portions into throws by 90 applying the pressure of forming dies in a direction transverse to the plane or planes of the formed throws.

3. The method of making die-forged 95 multi-throw crank-shafts having integral counter weights, which comprises first forming a substantially straight blank having longitudinally spaced portions of enlarged cross-section, then, while maintaining the axial portion of the blank substantially 100 straight, breaking down the enlarged portions to allocate metal for the counterweighted throws, and, then shaping the throws and journals substantially to the desired contour. 105

4. The method of making die-forged, 110 multi-throw crank-shafts having integral counter weights, which comprises first forming a substantially straight blank having longitudinally spaced portions of relatively 115 large and small cross sections, and, while maintaining the central portion of the blank substantially straight, die-forging the same to form the small portions into journals and the enlarged portions into counterweighted throws by successively applying the pressure of roughing-out and shaping dies transversely to the blank and substantially at right angles to the plane of the formed throws. 120

5. The method of making die-forged, 125 multi-throw crank-shafts having integral counterweights and journals on both of the arms of each throw, which comprises forming a substantially straight blank having longitudinally spaced protuberances or enlargements of substantially the dimensions and positions of the counterweighted throws, and then forming and shaping the journals and throws by applying the pres- 130

sure of forging dies in a direction transverse to the plane or planes of the formed throws.

6. The method of making die-forged, 5 multi-throw crank-shafts having integral counterweights and journals on both of the arms of each throw, which comprises forming a substantially straight blank having longitudinally spaced protuberances or enlargements of substantially the dimensions 10 and positions of the counterweighted throws, and then, and while maintaining the central portion of the blank substantially straight, die-forging the enlargements of 15 the blank into counterweighted throws and the other portions into journals by subjecting the blank successively to roughing-out and contour-shaping die impressions both adapted to apply pressure to the blank in a 20 direction substantially at right angles to the plane of the formed throws.

7. The process of forging multi-throw crank-shafts which comprises enlarging the cross-section of a plurality of spaced portions 25 of a bar to form a blank, then, while maintaining the axial portion of the blank substantially straight, partially dividing the enlargements transversely to allocate metal for the crank arms and pins, and then shaping the blank to substantially the desired 30 contour.

8. The process of forging multi-throw crank-shafts which comprises enlarging the cross-section of a bar at a plurality of spaced 35 portions corresponding in number to the throws, then partially dividing each enlargement by indenting opposite sides thereof between opposed elements of breaking down die-impressions and then die-shaping the 40 journals and throws substantially to the desired contour.

9. The process of making die-forged, 45 multi-throw crank-shafts having counterweights forged integrally therewith, which comprises reducing the cross-section of a plurality of longitudinally spaced portions of a bar to thereby enlarge the intermediate 50 portions, then transversely indenting the opposite sides of certain of the enlargements to partially divide the same and allocate metal for counterweighted crank arms, and then shaping the parts substantially to the desired contour.

10. The process of making die-forged, 55 multi-throw crank-shafts having counterweights forged integrally therewith, which comprises reducing the cross-section of a plurality of longitudinally spaced portions of a bar to form a plurality of enlargements, 60 one for each throw, then, while maintaining the central portion of the blank substantially straight, transversely indenting the opposite sides of each enlargement between opposed elements of a roughing-out die-im- 65 pression to partially divide the same and

allocate metal for the counterweighted arms and pin of the corresponding throws and then die-shaping the journals and counterweighted throws substantially to the desired contour.

11. The process of making die-forged, 70 multi-throw crank-shafts having integral journals and counterweights on both of the arms of each throw, which comprises reducing the cross-section of a bar at a plurality of longitudinally spaced portions, one for each journal, and thereby form a plurality of intermediate protuberances or enlargements, one for each throw, then, while maintaining the axial portion of the blank substantially straight, subjecting it to the action of roughing-out die-impressions having opposed elements for partially dividing each enlargement transversely and then to the action of shaping die-impressions to bring 80 the journals and counterweighted throws substantially to the desired contour.

12. The process of making die-forged, 85 multi-throw crank-shafts having integral journals and counterweights on both of the 90 arms of each throw, which comprises reducing the cross-section of a bar at a plurality of longitudinally spaced portions, one for each journal, and thereby forming a plurality of intermediate protuberances or enlargements, one for each throw, then subjecting the blank to the action of roughing-out die-impressions adapted to apply pressure to the blank substantially at right angles to the plane of the formed throws and having opposed transverse, wedge-shaped, die-elements for partially dividing each enlargement and thereby allocate metal for the corresponding counterweighted crank arms and pins, and then subjecting the rough-out blank to the 100 action of contour-shaping die-impressions.

13. The method of forging crank-shafts and the like, which comprises die-forging a heated bar to enlarge the cross-section of portions thereof, then subjecting the blank 110 to a second die-forging operation to partially transversely divide certain of the enlarged portions while preventing the axial elongation of such portion or portions, and then die-forging the blank to the desired contour.

14. The method of forging an integral crank-shaft or the like, which comprises die-forging a bar blank to enlarge the cross-section of a portion of the blank and reduce the cross-section of the adjacent portions, 115 then, and while preventing the axial elongation of the enlarged portion, transversely indenting the opposite sides thereof to partially divide the same and allocate metal for a pair of adjacent transverse arms or pro- 120 jections, and then die-shaping the blank to the desired contour.

15. The method of forging crank-shafts and the like, which comprises turning a heated bar between dies to reduce the cross- 125 130

section of spaced portions of the bar and enlarge the cross-section of the intermediate portion, then forging the blank between die-impressions having pairs of opposed elements for engaging the reduced portions of the blank and a pair of opposed wedge-shaped die-elements for partially transversely dividing the enlarged portion thereof to thereby allocate metal for two adjacent transverse arms or projections, and then die-forging the blank to the desired contour.

16. The method of forging an integral crank-shaft, which comprises turning a bar of substantially uniform cross-section between dies having an ovoidal recess to thereby enlarge the cross-section of a portion of the blank and reduce the cross-section of the adjacent portions, then subjecting the blank to die-impressions having opposed, wedge-shaped die elements to partially transversely divide the enlarged portion, and then die-fashioning the blank to shape the partially divided enlarged portion into the cheeks and pins of a crank and the reduced portions into journals, all of substantially the desired contour.

17. The method of forging an integral crank-shaft, which comprises first turning a bar between forging dies having impressions provided with rounded surfaces to reduce longitudinally spaced sections of the blank and form journal portions, and also enlarge an intermediate section, then subjecting the blank to impressions having opposed elements for engaging and roughing out the journal portions and opposed, transverse, die-elements for partially dividing the enlarged portions to thereby allocate metal for a pair of counterweighted crank arms and an intermediate pin, and then dieshaping the counterweighted crank arm, pin and journal portions of the blank substantially to the desired contour.

18. The method of forging an integral crank-shaft, which comprises turning a bar of substantially uniform cross-section between forging dies having channels provided with one or more oval-shaped recesses to reduce the cross-section of longitudinally spaced portions of the blank and enlarge the cross-section of one or more intermediate portions, and then, and while maintaining the axial portion of the blank substantially straight, die-forging the blank to form the reduced portion into journals and enlarged portions or portion each into a throw comprising a crank pin and a pair of crank arms or cheeks having integral counterweights.

19. The method of forging an integral crank-shaft, which comprises turning a bar of substantially uniform cross-section between forging dies having channels provided with one or more oval-shaped recesses to reduce the cross-section of longitudinally spaced portions of the blank and enlarge the

cross-section of one or more intermediate portions, and then die-forging the blank to form the reduced portions into journals and the enlarged portions each into a throw comprising a crank-pin and a pair of crank arms or cheeks having integral counterweights, by subjecting the blank to die-impressions adapted to apply pressure to the blank transversely of the plane or planes of the formed throws.

20. The method of forging an integral crank-shaft, which comprises turning a bar of substantially uniform cross-section between forging dies having channels provided with one or more oval-shaped recesses to reduce the cross-section of longitudinally spaced portions of the blank and enlarge the cross-section of one or more intermediate portions, and then die-forging the blank to form the reduced portions into journals and the enlarged portions each into a throw having a pair of integrally counterweighted crank arms or cheeks, by subjecting the blank first to the action of roughing-out die impressions adapted to apply pressure substantially at right angles to the plane of the formed throws and having opposed wedge-shaped elements for partially dividing each enlargement transversely, and then to the action of contour-shaping die-impressions.

21. The method of forming die-forged, multi-throw crank-shafts, which comprises first forming a substantially straight blank having substantially symmetrical, longitudinal portions alternately of reduced and enlarged cross-section with the grain or fiber of the metal adjacent the surface and axes of the blank substantially parallel thereto respectively, then die-forging the reduced portions into journals and the enlarged portions each into a counter-weighted throw by subjecting the blank successively to roughing-out and contour-shaping impressions both adapted to apply pressure to the blank transversely to the plane or planes of the formed throws and having opposed wedge-shaped and substantially abutting die-elements respectively for transversely dividing the enlarged portions of the blank to thereby form the spaces between the counterweighted arms or cheeks of the throws.

22. Apparatus for forging multi-throw crank-shafts comprising relatively reciprocating die members having "breaking down" or "roughing out" impressions arranged to apply pressure to the blank transversely to the plane or planes of the throws formed thereby and having pairs of transverse, opposed wedge-shaped die-elements for partially dividing enlargements in the blanks and thereby allocate metal for the crank arms or cheeks of the throws.

23. Apparatus for forging a multi-throw, counterweighted crank-shaft from a blank having a plurality of protuberances, comprising

- ing relatively reciprocating die-members having impressions for forming the throws in a common plane by the application of pressure to a blank in a direction substantially at right angles to the plane of the formed throws, the impressions of the die-members having pairs of opposed elements extending transversely of the die-cavity and on opposite sides of the axis of the cavity and arranged to divide the 10 protuberances of the blank and form the spaces between the counterweighted crank arms or cheeks of the throws.
24. Apparatus for forging a multi-throw, counterweighted crank-shaft from a blank 15 having a plurality of protuberances, comprising relatively reciprocating die-members having impressions for forming the throws by the application of pressure to the blank in a direction transverse to the plane or 20 planes of the formed throws, the impressions of the die-members having pairs of opposed wedge-shaped elements for partially dividing the protuberances of the blank transversely and allocating metal for integral 25 counterweights.
25. Apparatus for forging a multi-throw crankshaft from a substantially straight blank having a plurality of protuberances, one for each throw, which comprises relatively reciprocating die-members having substantially 30 symmetrical impressions for roughing out the journals and counterweighted throws by the application of pressure to the blank substantially at right angles to the common 35 plane of the formed throws, the impressions of the die-members having pairs of opposed, transverse, wedge-shaped die-elements for partially dividing the protuberances of the blank and allocating metal to form the spaced 40 counterweighted crank arms or cheeks of the throws.
26. Apparatus for forging counterweighted, multi-throw crank-shafts from a rolled blank of substantially uniform cross-section, 45 comprising relatively reciprocating die-members having impressions for forming the
- bar into a substantially symmetrical blank having alternate, convexly and concavely rounded longitudinal portions of enlarged and reduced cross-section respectively, and 50 impressions for forming the reduced portions into journals and the enlarged portions each into counterweighted throws by the application of pressure to the blank transversely of the plane or planes of the formed 55 throws.
27. The method of making multi-throw, counterweighted crank-shafts comprising the following die-forging operations: (1) forming a bar into a substantially straight 60 blank having longitudinal spaced protuberances or enlargements having convexly rounded surfaces, (2) re-shaping the blank to bring the longitudinal sections of the protuberances into substantially rectangular 65 form, (3) forming the counterweighted throws, one from each of the protuberances, by the application of pressure to the blank transversely of the formed throws, and (4) bringing the journals and throws substantially 70 to the desired contour.
28. Apparatus for forging a multi-throw crank-shaft from a substantially straight blank having a series of reduced portions and intermediate enlargements, one for each 75 throw, comprising relatively reciprocating die members having impressions for roughing out the journals and throws by application of pressure in a direction transverse to the plane or planes of the formed throws, the 80 opposed journal forming elements of the impressions being arranged to engage reduced portions of the blank on opposite sides of each enlargement and prevent the axial elongation thereof and the throw-forming cavities having pairs of opposed, wedge-shaped 85 die-elements for partially transversely dividing each enlargement of the blank and thereby allocate metal for the crank arms and pins.

ALBERT J. LARCHER.
